[57] CLAIM

The ornamental design for the sailboard speedometer,
as shown and described.

DESCRIPTION

FIG. 1 is a side elevational view of a sailboard speedometer showing my new design;

FIG. 2 is a side elevational view thereof with the sensor and convertor cord omitted for ease of illustration;

FIG. 3 is a top plan view of FIG. 2;

FIG. 4 is an opposite side elevational view of FIG. 2;

FIG. 5 is a bottom plan view of FIG. 3;

FIG. 6 is a left end elevational view of FIG. 2;

FIG. 7 is a right end elevational view of FIG. 2;

FIG. 8 is a side elevational view of the sensor portion of
the speedometer, with the transmitter and converting
cord omitted for ease of illustration;

FIG. 9 is an opposite side elevational view of FIG. 8;

FIG. 10 is a top plan view of FIG. 8;

FIG. 11 is a bottom plan view of FIG. 8;

FIG. 12 is a left end elevational view of FIG. 8;

FIG. 13 is a right end elevational view of FIG. 8;

FIG. 14 is a side perspective view of FIG. 1; the broken-line showings being environmental only and form no
part of the claimed design.
